UNITED STATES PATENT OFFICE.

CHARLES L. CESSNA, OF WEBSTER CITY, AND JOHN V. WARDEN, OF BLAIRSBURG,
IOWA.

DEMOUNTABLE-TUBE RADIATOR.

1,370,186.

Specification of Letters Patent.

Patented Mar. 1, 1921.

Application filed July 28, 1919. Serial No. 313,756.

To all whom it may concern:

Be it known that we, CHARLES L. CESSNA and JOHN V. WARDEN, each a citizen of the United States of America, and resident of Webster City and Blairsburg, respectively, in Hamilton county, Iowa, have invented a new and useful Demountable-Tube Radiator, of which the following is a specification.

The object of this invention is to provide improved means of constructing a radiator adapted to be employed in the cooling system of an explosive engine.

A further object of this invention is to provide convenient means for separating the tanks of a radiator.

A further object of this invention is to provide convenient means for removably and replaceably connecting the tanks of a radiator.

A further object of this invention is to provide a construction for convenient removal, replacement and substitution of a radiator tube.

A further object of this invention is to provide convenient means, other than solder, for removably and replaceably connecting a radiator tube to the tanks of a radiator.

A further object of this invention is to provide an improved construction for the bottom of the upper tank of a radiator.

A further object of this invention is to provide an improved construction for a radiator tube adapting it to be removed and replaced by means of a wrench of peculiar form without restricting passage through said tube.

Our invention consists in the construction, arrangement and combination of elements hereinafter set forth, pointed out in our claims and illustrated by the accompanying drawing, in which—

Figure 1 is a front elevation and Fig. 2 a side elevation of a radiator embodying our improvements. Fig. 3 is a cross-section 45 on the indicated line 3—3 of Fig. 2. Fig. 4 is a vertical section on the indicated line 4—4 of Fig. 3, on an enlarged scale, portions being omitted to economize space. Fig. 5 is a bottom end view of one of the tubes. Fig. 6 is an elevation and Fig. 7 is a bottom 50 end view, on an enlarged scale, of a wrench employed with the tubes.

In the construction of the device as shown the numeral 10 designates a bottom tank, 11 55 an upper tank and 12 any one of a series

of tubes connecting and providing for a circulation of cooling medium, such as water, between the tanks. The bottom tank 10 may be of any desired form and construction and preferably has the characteristic of a plane 60 top plate 13 provided with a series of threaded or tapped holes, one for each of the tubes 12. The top tank 11 may be of any desired form and construction; but preferably has two particular characteristics about to be 65 described. One characteristic of the upper tank 11 is that it is formed with a removable and replaceable top plate 14 secured to the walls of the tank by cap screws 15 operable from the exterior of the tank and sealed in 70 any suitable manner, such as with a common gasket. This is to give access conveniently to the interior of the tank 11 for manipulation, on occasion, of the tubes 12. The other 75 desirable characteristic of the tank 11 is that it is formed with a bottom plate 16 having a series of depressed or depending bosses 17, which are struck or pressed outwardly therefrom and are apertured centrally in their bottoms to receive the tubes 12 loosely 80 therein. The bottom tank 10 and upper tank 11 are connected suitably at their corners by stays 18, in this instance four in number, which stays are secured in any desired manner at their ends to and serve to separate 85 or space as well as connect the tanks. We have shown the ends of the stays soldered to the outer surfaces of the tanks 10, 11 in a manner common in sheet metal work including radiators. Either end of a stay may 90 be removed from a tank by prying it off with a tool and be re-soldered conveniently as desired. Each tube 12 is formed with a threaded end portion adapted to pass freely through a hole of a boss 17 and be screwed 95 into a tapped hole in the plate 13, and a non-threaded end portion adapted to fit loosely in said hole in the boss. To facilitate placing and removing the tube by screwing in the plate 13, a thickened portion 19 is formed 100 in and fills a segment of the lower end portion of the tube 12, and the inner wall of said thickened portion is inclined toward the adjacent wall forming the bow of the segment, and a wrench 20, having a shank 105 adapted to fit loosely within the tube and extend longitudinally through it, is formed with a notch 21 in one end adapted to accommodate the boss 19 and interengage with said boss in such manner as to prevent inde- 110

pendent rotation of the wrench and insure turning of the tube thereby. The wrench is formed with a flattened end portion or head 22 adapted to be engaged by pliers to 5 manually turn the wrench. Through the use of the tool the tubes may be unseated or seated, and when seated said tubes preferably have their upper ends flush with the top surface of the bottom plate of the tank 10 16, in order that the tank may drain properly on occasion. Packing 23 is placed on the upper surface of the bottom of each boss 17 (Fig. 4) and a gland 24 is screwed in each boss and applies a pressure to said 15 packing, the boss being interiorly threaded to receive the gland. In such manner the upper end portion of the tube 12 is sealed in its boss. In order that the gland 24 may seat with its upper end flush with the upper 20 end of the tube, said gland is formed with spanner seats or notches 25 adapted to receive a spanner formed on the head 22 of the wrench. The spanner may be employed to seat or unseat the glands, and is manipulated by turning the wrench as with pliers. The thickened portion 19 restricts the bore of the tube 12 normally and would obstruct the desired flow of cooling medium through 25 said tube. To avoid such condition, the tube 30 12 is formed with an arcuate notch 26 diametrically opposite the thickened portion 19, which notch has a capacity compensatory of the normal restriction caused by the thickened portion.

35 Any desired number of tubes 12 may be employed and they preferably are arranged in parallel rows, the number of which rows also may vary.

Under the construction as illustrated and 40 described, the tubes 12 may be removed and replaced or substituted by others selectively, or, either tank may be removed, repaired and replaced or substituted by another with a minimum expenditure of time and labor, 45 and the assembled device is effective in providing an air-cooled element of a water-cooling system for explosive engines.

We do not wish to be understood as limited to the exact construction and arrangement of parts as shown or described, since 50 the same may be modified in many particulars without departing from our invention within the scope of the appended claims.

We claim as our invention—

55 1. A radiator comprising upper and lower tanks spaced apart and tubes detachably connecting and communicating at opposite ends with said tanks, the connection between the tubes and the lower tank being 60 a threaded joint, each tube being formed with an interior engaging means adapted to be engaged by a wrench passed through the tube.

65 2. A radiator comprising upper and lower tanks spaced apart and tubes detach-

ably connecting and communicating at opposite ends with said tanks, the connection between the tubes and the lower tank being a threaded joint, each tube being formed with an interior engaging means located at 70 the lower threaded end of said tube, which engaging means is adapted to be engaged by a wrench extending within said tube.

3. A radiator comprising upper and lower tanks spaced apart and tubes detachably connecting and communicating at opposite ends with said tanks, the connection between the lower tank and each tube being a threaded joint, each tube being formed with engaging means located within the 75 threaded lower end thereof and also formed with a notch opposite said engaging means, said engaging means being adapted to be engaged by a wrench extending within said tube.

4. A radiator comprising upper and lower tanks spaced apart and tubes detachably connecting and communicating at opposite ends with said tanks, the upper tank being formed with apertured depending 80 bosses in its bottom through which said tubes extend, and packed glands mounted in said bosses and surrounding and sealing said tubes to said bottom, no portion of any of said tubes or glands projecting above the 85 horizontal plane of the upper face of said bottom.

5. In a radiator, a tank formed with a bottom plate having a series of apertured bosses, said bosses extending below said 90 plate and being interiorly threaded, tubes mounted loosely in said bosses and extending through the apertures thereof, packing in said bosses around said tubes, a gland screwed in each boss, each gland being 95 formed with spanner notches in its upper end.

6. A radiator tube formed with a threaded end portion and also formed with an integral engaging means within said threaded end portion adapted to be engaged by a wrench extending within said tube.

7. A radiator tube formed with a threaded end portion and also formed with an integral segmental engaging means within 115 said threaded end portion adapted to be engaged by a wrench extending within said tube.

8. A radiator tube formed with a threaded end portion and also formed with an integral engaging means within said threaded end portion adapted to be engaged by a wrench extending within said tube, and also formed with a notch compensatory to the tube restriction of said engaging means.

Signed at Webster City, in the county of Hamilton and State of Iowa, this 30th day of June, 1919.

CHARLES L. CESSNA.
JOHN V. WARDEN.
